Patented July 29, 1919.

UNITED STATES PATENT OFFICE.

LUTHER C. MEYERS, OF BRIDGETON, NEW JERSEY.

PRESS-FRAME.

1,311,412.

Specification of Letters Patent. Patented July 29, 1919.

Application filed March 8, 1917. Serial No. 153,347.

To all whom it may concern:

Be it known that I, LUTHER C. MEYERS, a citizen of the United States, and resident of Bridgeton, in the county of Cumberland, 5 and in the State of New Jersey, have invented a certain new and useful Improvement in Press-Frames, and do hereby declare that the following is a full, clear, and exact description thereof.

10 My invention relates to presses, such as cutting and punching presses of the open throat type wherein the frame extends upward and forward from the base and overhangs the latter. As ordinarily made press 15 frames for this type of press have been made of a one piece casting and when, as often happens, they are broken by accident, or overload, the entire frame is ruined and must be replaced, and at considerable loss 20 because the whole frame is quite expensive. The object of my invention is to avoid the loss of the entire frame should breakage occur and to diminish the danger of breakage from overload, and my invention, 25 broadly stated, consists in constructing the base, head and connecting member between base and head of separate castings and connecting the base and head members by tie rods which will take the tensile stresses 30 which have to be borne by the frame of the type of presses in question.

In the accompanying drawings, I illustrate my invention as embodied both in cutting and punching presses, in which drawings—

Figure 1 is a side elevation of a cutting press frame embodying my invention;

Fig. 2 is a front elevation thereof;

Fig. 3 is a side elevation of a punching 40 press embodying my invention;

Fig. 4 is a front elevation thereof.

Referring to the cutting press frame shown in Figs. 1 and 2, it will be seen that it is composed of a base member 10 having 45 a plane, or flat top, a head member which is composed of two similar elements 11, which have half boxes 12 to furnish bearings for the shaft which extends from side to side of the press, and a body member 13, 50 which, at its lower end rests upon the base at the rear thereof, the two being secured together by bolts 14, and at its upper end at each side has secured to it by bolts 15 the two elements forming the head member 11, 55 the abutting faces of the various members being plane, or flat. The body member 13

inclines upward and forward so that as will be seen from Fig. 1 of the drawings the ram reciprocating shaft overhangs the work on the bed of the press. At each side of the 60 press, and extending continuously from the bottom of the base 10 upward through an opening in the same and upward through openings in the body 13 and the head elements 11, and emerging on the top of the 65 latter, is a tie rod 16, which at each of its projecting ends has a nut 17 and said tie rods, as may be seen by reference to Fig. 1, extend at an incline upward and forward, their position being such that they are intermediate the fulcrum, or bearing point upon which the body member 13 under load tends to rock upon the base 10, and the line of thrust between the shaft supported by the head elements 11 and the base so that said 70 tie rods are practically in the line of greatest tensile strains, and hence, take the tensile stress which the frame must bear. Due to the location and inclination of said tie rods, I secure the object of my invention, 75 namely, a sectional, or built up frame, and one strengthened to support the tensile stress by a single pair of tie rods, one of which is at either side of the frame.

In Figs. 3 and 4, I show my invention embodied in a punching press, the frame of which consists of a base member 10^a, a head member 11^a and an intermediate body member 13^a, the head in this case consisting of a single member since the shaft extends from 80 front to back of the press. There are two tie rods 16^a which extend upward and forward through the frame sections in a similar position to those of the press shown in Figs. 1 and 2, and having nuts 17^a on their 85 protruding ends.

The ram slides in guides upon and at the front of the body member 13, or 13^a.

If from accident, or overload any portion of the frame of the press breaks, the only 100 part requiring to be replaced is the broken member, and thus there is no such serious loss as happens in the ordinary construction when the whole frame is cast in one piece.

Having thus described my invention what 105 I claim is—

1. A press frame for open throated presses comprising base, head and body members made of separate pieces, and a pair of tie rods, one at either side of the press, extending 110 through and joining said pieces, said tie rods being situated in rear of the line

of thrust between head and base members and forward of the fulcrum point upon which said connected members tend to rock.

2. A press frame for open throated presses comprising base, head and body members made of separate pieces, and a pair of tie rods, one at either side of the press, extending through and joining said pieces, said tie rods being situated in rear of the line of

thrust between head and base members and 10 forward of the fulcrum point upon which said connected members tend to rock, and said tie rods being inclined upward and forward.

In testimony that I claim the foregoing 15 I have hereunto set my hand.

LUTHER C. MEYERS.
